WALL RECEPTACLE

George P. Wiedman, North Tonawanda, N. Y.

Application August 5, 1947, Serial No. 766,144

6 Claims. (Cl. 232—19)

1

This invention relates to receptacles and more particularly to a receptacle mounted in a wall of a building for receiving mail and other articles which are insertable from one side of the wall and removable from the opposite side thereof.

It is the principal object of the invention to provide a receptacle adapted to be mounted in a building wall, particularly an outside wall of a house, to receive mail and small packages which are insertable from the outside and removable from the inside of the wall.

Another object is to provide such a receptacle in which its contents cannot be readily removed from the side from which the articles were inserted thereby to prevent pilferage of the contents of the receptacle.

Another object is to provide such a receptacle which is weather-proof and which also prevents the transfer of heat from one side to the opposite side of the wall in which the receptacle is arranged.

Another object is to provide such a receptacle which can be fabricated of light-weight sheet metal.

A further object is to provide such a receptacle which can be readily mounted in the wall of a building.

A further object is to provide such a receptacle which is simple in construction, inexpensive to manufacture, easily operable and not likely to get out of order or require repairs.

Other objects and advantages of the invention will be apparent from the following description and drawings wherein:

Fig. 1 is a front elevation of a fragmentary portion of a building wall and showing the receptacle embodying the present invention mounted therein.

Fig. 2 is a vertical sectional view taken on line 2—2, Fig. 1, and showing one side of the receptacle in elevation.

Fig. 3 is an enlarged vertical transverse sectional view of the receptacle shown in Figs. 1 and 2 and showing the rear or inside door of the receptacle in an open position.

Fig. 4 is an enlarged fragmentary elevation of the upper portion of the receptacle shown in Fig. 1 and showing the front doors of the receptacle in an open position.

Fig. 5 is a vertical transverse sectional view thereof taken generally on line 5—5, Fig. 4.

Fig. 6 is a fragmentary sectional view thereof taken on line 6—6, Fig. 5.

Fig. 7 is an enlarged fragmentary horizontal sectional view taken on line 7—7, Fig. 3.

2

Fig. 8 is an enlarged fragmentary elevational view taken on line 8—8, Fig. 3.

The receptacle embodying the present invention is shown as having a box-like frame or body, represented generally by the numeral 10. This body 10 is shown as being formed of sheet metal and including side walls 11—11, a top wall 12, a bottom wall 13 and a front wall 14. The rear of the body 10 is open and formed to provide a narrow marginal flange 15 which extends inwardly of the body parallel to the front wall 14. The upper portion of the front wall is cut out to provide a rectangular opening 16. A rectangular frame 18, each side of which is shown as being L-shaped in cross section is mounted in any suitable manner on the front wall 12 in such a position as to surround the opening 16 therein. The forwardly projecting continuous flange 19 of this frame 18 provides shoulders against which adjacent siding, bricks, shingles or other outside wall surface material of the building abuts.

Referring to Figs. 1 and 2, the present receptacle is shown as mounted in an outside wall of a building. The body 10 is shown as being of such frontal width as to snugly fit between a pair of adjacent studs 21 of the building. Upper and lower horizontal support members 22 are interposed between the studs 21 and engage the top and bottom walls 12, 13 respectively, of the body 10 and thereby support the receptacle at the desired vertical location on the building wall. The exterior of this building wall is shown as being faced with clapboards 23 which are so cut as to abut the flange 19 of the rectangular frame 18 on the front of the receptacle. In this manner the front of the receptacle is substantially flush with the exterior of the wall although it will be understood that the front of the box can be recessed inwardly of the wall, such as when the wall is faced with brick or stone.

It will be noted that the vertical sides of the frame 18 extend laterally beyond the sides of the body 10, the exposed rear faces of these vertical sides thereby providing stop surfaces 24 which engage the front faces of the studs and prevent the receptacle from being moved farther into the wall. Also with substantial portions of the clapboards 23 overlapping the front wall 14, the receptacle is held against movement outwardly of the building wall.

It will also be noted that only that portion of the front of the receptacle surrounded by the frame 18 is shown as being exposed. If desired, the frame 18 can be constructed with a larger vertical distance between the upper and lower

horizontal sides of this frame so that any desired amount of surface of the front wall 14 of the receptacle can be exposed.

Referring again to the construction of the receptacle, the open rear end of the box-like body or frame 10 is covered by a hood 25 which is preferably formed of sheet metal to provide a rear wall 26, side walls 27—27, and an attaching flange 28 which extends continuously around the edge of the hood. The hood 25 is removably mounted on the body 10 and for this purpose the flange 28 of the hood is shown as opposing the flange 15 on the body and secured thereto by screws 29 or in any other suitable manner.

The lower part of the rear wall 26 of the hood 25 is provided with an opening 30 to permit access to the interior of the box like body 10 and to remove the contents therefrom. This opening 30 preferably extends across the full width of the rear wall 26 of the hood 25. A door 31 hinged along its lower edge to the hood 25 in any suitable manner serves as a closure for the opening 30. The door 31 carries latch means for securing the door in a closed position, such latch means being shown as comprising a latch bar 32 on the inner end of a pivot rod 33 extending through the upper part of the door 31 and a handle 34 on the outer end of the pivot rod 33. By turning the handle 34 it will be seen that the pivotally mounted latch bar 32 can be turned into and out of engagement with a marginal portion of the rear wall 26 of the hood 25, as shown in Fig. 5.

To inhibit the transfer of heat from opposite sides of the rear wall 26 the same is preferably lined with sheet insulating material 35 such as cork or the like, this insulation being shown as also extending between the connected flanges 15 and 28. The inside of the rear door 31 is also faced with similar sheet insulating material as shown at 36.

It will be noted that the rear wall 26 of the hood 25 is arched rearwardly so as to house a substantially triangular space in vertical cross section. The space housed by the rear wall 26 of the hood 25 jointly with the interior of the box like body or frame 10 provide a compartment 37 in the upper part of which a bucket shaped receiver indicated generally at 38 is arranged.

The receiver 38 is adapted to receive mail and other small packages inserted through the opening 16 in the front wall 14 of the body 10 and when thereafter actuated deposits or dumps these articles into the lower part of the compartment 37. To this end the receiver 38 is shown as being formed of sheet metal into generally C-shaped form in vertical cross section, as shown in Figs. 3 and 5, and having a front upper panel 39, a lower panel 40 and an intermediate back panel 41. It will be noted that the upper and lower panels 39 and 40, respectively, are arranged at an angle to each other and are forwardly convergently directed so that when the upper panel 39 is in a vertical position the lower panel 40 is remote from the front wall 14 and extends downwardly and forwardly, as shown in Fig. 3, and when the lower panel 40 is in a horizontal position adjacent the front wall 14, the upper panel 39 projects forwardly and downwardly through the opening 16, as shown in Fig. 5. In this manner the upper panel 39 can serve as a closure member for the upper part of the opening 16 in the front wall 14. A side panel or end wall 42 is provided on each end of the receiver 38.

To permit this movement of the receiver 38, means are provided for pivotally mounting the

receiver on the body or frame 10. For this purpose, each end wall 42 of the receiver 38 is pivotally mounted on the adjacent side wall 11 of the body 10 by a bearing assembly. Such bearing assembly is shown as comprising a bearing cup 43, a second bearing cup 44 of slightly smaller diameter rotatably received thereby, and a connecting bolt 45. The bearing cup 43 is shown as arranged on the exterior of the corresponding end wall 42 adjacent its upper part and secured against rotation relative to this end wall by an arm 46 which extends substantially parallel to the front upper panel 39 of the receiver 38 and has its extremity reversely bent to hook around the front edge of this end wall, as indicated at 48. The base of the second bearing cup 44 is shown as secured to the inside of the corresponding side wall 11 of the body 10 by a pair of screws 49. The connecting bolt 45 is arranged in registered openings provided in the corresponding side wall 11, cups 43 and 44, and end wall 42, nuts 50 being shown as arranged on the inner end of the bolt 45 to maintain the same in position. By a bearing assembly of this construction the receiver 38 can be readily assembled in the body 10 and also provides a substantial bearing surface. The axes of these bearing assemblies are coincident so that the receiver can be moved about a horizontal axis.

The lower portion of the opening 16 in the front wall 14 of the body 10 is adapted to be closed off by a lower front door 51 which extends across the full longitudinal width of the opening 16. This door 51 is shown as being hinged along its lower horizontal edge to the front wall 14 in any suitable manner, as indicated at 52. The upper horizontal edge of this door 51 is formed to provide a rearwardly offset lip 53 adapted to cooperate with the reversely bent lower edge 54 of the upper front panel 39 of the receiver 38, as shown in Fig. 3, thereby to provide an effective seal along this joint.

Means are provided to seal the joints between the vertical edges of the front upper panel 39 and the lower front door 51 and the cooperating vertical edges of the front wall 14. To this end the outer portion of the lower front door 51 is laterally extended along each vertical edge and formed to provide a reversely bent L-shaped flange 55, the laterally extending part of which overlies a rearwardly offset flange 56 formed on the corresponding vertical edge of the front wall 14 of the body 10, a sealing strip 58 of cork or other suitable material being interposed between the cooperating faces of the flanges 55 and 56 and carried by the flange 55, as shown in Fig. 7. Similarly, the outer portion of the upper front panel 39 of the receiver 38 is laterally extended along each vertical edge to provide a lateral flange 59 which opposes and overlies the corresponding flange 56 on the front wall 14 of the body 10, a sealing strip 60 similar to the strip 58 being carried by the flange 59 and engageable with the flange 56. It will be noted that the flanges 55 on the lower front door 51 terminate short of the hinged connection 52 of the door, and the lateral flanges 59 on the upper front panel 39 are provided only along the outer edges of this panel so that these flanges 55 and 59 will not interfere with the flanges 56 when the panel is raised and the lower front door 51 is opened.

A handle 61 is provided on the outside of the front upper panel 39 to facilitate manual manipulation of the receiver 38. When the receiver 38 is moved to the article receiving position shown

in Fig. 5, the lower front door 51 is moved from its vertical closed position to a substantially horizontal forwardly projecting open position such as shown in Fig. 5. For this purpose, a link 62 connecting the receiver 38 with the door 51 is provided on each side of this door. One end of each link 62 is shown as pivoted at 63 to the corresponding flange 55 of the door 51 and the opposite end is pivoted at 64 to the corresponding end wall 42 of the receiver 38, the pivot 64 being at a higher elevation than the pivot 63. A portion of each end wall 42 adjacent the corresponding link 62 is shown as being offset inwardly of the receiver as indicated at 65 thereby to accommodate the movement of the links 62. It will thus be seen that with the receiver 38 and lower front door 51 in the position shown in Fig. 3, by lifting the handle 61 the receiver 38 is rotated in a clockwise direction and the door 51 in a counterclockwise direction to the position shown in Fig. 5. In this position of the parts shown in Fig. 5, mail, small packages and other articles can be inserted through the uncovered opening 16 and placed on the floor or lower panel 40 of the receiver, this panel 40 being horizontal in this position and substantially in line with the opened lower front door 51. Thereafter the handle 61 is pulled down whereby the receiver 38 is rotated in a counterclockwise direction and the door 51 in a clockwise position from the position shown in Fig. 5 to the position shown in Fig. 3. In so moving the receiver 38, the lower panel 40 supporting the inserted articles is moved to the rear away from the front wall 14 and tilted or tipped so that the articles are dumped into the lower part of the compartment 37 from which they can be removed through the opening 30 by opening the rear door 31.

Means are provided for locking the receiver in the position shown in Fig. 3 so that the receiver 38 and lower front door 51 cannot be opened to give access to the interior of the receptacle. For this purpose, the rear wall 26 of the hood 25 carries a latch comprising a latch bar 68 on the inner end of a pivot pin 69 extending through the rear wall 26 and a turn handle on the rear or outer end of this pivot pin. Referring to Fig. 8, the latch bar 68, when in the horizontal position shown by broken lines in this figure, is adapted to enter an opening 70 provided in the adjacent part of the back panel 41 of the receiver 38 and be turned to the full line position shown to engage a latch plate 71 carried by the back panel 41 adjacent one side of the opening 70 therein. The latch plate 71 is shown as being formed to provide a pair of horizontally spaced rearwardly projecting rounded protrusions 72—72 forming a land 73 therebetween which engages the latch bar 68. Thus the land 73 is slightly flexibly mounted and when engaged by the latch bar 68 serves to hold the receiver 38 in a firmly latched immovable position and also prevents the latch bar from being casually or unintentionally displaced.

It will be noted that even with the receiver 38 in an unlatched condition it is difficult for a person to insert his hand and arm through the opening 16 in the front wall 14 and reach down into the bottom of the compartment 37 inasmuch as the front upper panel 39 of the receiver 38 and the front lower door actuated in response to the movement thereof would have to be separated a substantial extent and hence bring the forward edge of the lower panel 40 close to the front wall 14. Pilferage of the contents of the receptacle

can be further prevented by providing the free edge of the lower panel 40 with serrations (not shown) which will engage the person's hand or arm and thereby deter further attempts to remove the contents.

From the foregoing it will be seen that the present invention provides a wall receptacle of simple and inexpensive construction which permits mail and small articles to be inserted from one side of the wall and removed from the opposite side and which cannot be readily pilfered. Further, the receptacle can be easily installed in a wall either in the original construction of the wall or after the wall has been erected.

I claim:

1. A receptacle for receiving mail and small packages and adapted to be mounted in a wall, comprising a box-like body having a front wall provided with an opening therein and a rear wall provided with an opening therein, a door for said second opening, a receiver arranged within said body adjacent said first opening, means pivotally mounting said receiver on said body, said receiver having a panel adapted to close off and uncover the upper portion of said first opening, a second door operatively arranged to close off and uncover the lower portion of said first opening, and means operatively connecting said second door to said receiver whereby said second door is moved in response to the movement of said receiver.

2. A receptacle for receiving mail and small packages and adapted to be mounted in a wall, comprising a box-like body having a front wall provided with an opening in the upper part thereof and a rear wall provided with an opening in the lower part thereof, a door for said second opening, a receiver arranged within said body adjacent said first opening, means pivotally mounting said receiver on said body so as to be movable about a horizontal axis, said receiver having a panel adapted to close off and uncover the upper portion of said opening and also having a second panel adapted to receive and dump said mail and small packages inserted through said first opening, a second door movable about a horizontal axis and adapted to close off and uncover the lower portion of said first opening, and a link pivotally connected to said receiver and to said second door whereby said second door is moved in response and in an opposite direction to the movement of said receiver.

3. A receptacle for receiving mail and small packages and adapted to be mounted in a wall, comprising a box-like body having a front wall provided with an opening in the upper part thereof and a rear wall provided with an opening in the lower part thereof, a door for said second opening, a receiver arranged within said body adjacent said first opening, means pivotally mounting said receiver on said body so as to be movable about a horizontal axis, said receiver having spaced upper and lower panels arranged at an angle to each other whereby said lower panel is in a tilted position remote from said front wall when said receiver has been moved so that said upper panel is in a position closing off said upper portion of said first opening and whereby said lower panel is in a substantially horizontal position adjacent said front wall when said receiver has been moved so that said upper panel is in a position uncovering said upper portion of said first opening, a second door movable about a horizontal axis and adapted to close off and uncover the lower portion of said first opening, and a link pivotally connected to said re-

ceiver and to said second door whereby said second door is moved in response and in an opposite direction to the movement of said receiver.

4. A receptacle for receiving mail and small packages and adapted to be mounted in a wall, comprising a box-like body having a front wall provided with an opening in the upper part thereof and a rear wall provided with an opening in the lower part thereof, a door for said second opening, a receiver arranged within said body adjacent said first opening, means pivotally mounting said receiver on said body so as to be movable about a horizontal axis, said receiver having spaced upper and lower panels arranged at an angle to each other whereby said lower panel is in a tilted position remote from said front wall when said receiver has been moved so that said upper panel is in a position closing off said upper portion of said first opening and whereby said lower panel is in a substantially horizontal position adjacent said front wall when said receiver has been moved so that said upper panel is in a position uncovering said upper portion of said first opening, a second door hinged along the lower edge of said first opening and movable from a vertical position closing off the lower portion of said first opening to a substantially horizontal forwardly projecting position in which said first opening is uncovered, and a link on each side of said second door and pivotally connected to said second door and to said receiver whereby said upper panel and said second door cooperates to open and close said first opening.

5. A receptacle for receiving mail and small packages and adapted to be mounted in a wall, comprising a box-like body having a vertical front wall provided with an opening in the upper part thereof and a rear wall provided with an opening in the lower part thereof, a door for said second opening, a bucket shaped receiver for receiving said mail and small packages inserted through said first opening and dumping the same into the lower part of such body from whence they can be removed through said second opening, means pivotally mounting said receiver

45

within said body adjacent said first opening, said receiver having spaced upper and lower panels angularly arranged to each other and forwardly convergently directed, said upper panel being adapted to close off and uncover the upper portion of said first opening, a second door operatively arranged to close off and uncover the lower portion of said first opening, and means operatively connecting said second door to said receiver whereby said second door is moved in response to the movement of said receiver.

6. A receptacle for receiving mail and small packages and adapted to be mounted in a wall, comprising a box-like body having a vertical front wall provided with an opening in the upper part thereof and a rear wall provided with an opening in the lower part thereof, a door for said second opening, a bucket shaped receiver for receiving said mail and small packages inserted through said first opening and dumping the same into the lower part of such body from whence they can be removed through said second opening, said receiver having spaced upper and lower panels angularly arranged to each other and forwardly convergently directed, a back wall connecting said panels and an end wall on each of said receiver, means pivotally mounting the upper part of each of said end walls on the adjacent one of said side walls whereby said receiver is oscillatable about a horizontal axis, said upper panel being adapted to close off and uncover the upper portion of said first opening, a second door hinged along the lower edge of said first opening and movable from a vertical position closing off the lower portion of said first opening to a substantially horizontal forwardly projecting position in which said first opening is uncovered, and a link pivotally connecting each of said end walls with said second door whereby said upper panel and said second door cooperate to open and close said first opening.

GEORGE P. WIEDMAN.
